[57] CLAIM

The ornamental design for a wall-type insect electrocutor, substantially as shown and described.

DESCRIPTION

FIG. 1 is a front elevation of the insect electrocutor;
FIG. 2 is a top plan view of FIG. 1;

FIG. 3 is a plan view looking at the bottom of FIG. 1;

FIG. 4 is a rear elevation of FIG. 1;

FIG. 5 is an elevation looking at the right-hand end of
FIG. 1, the opposite end elevation thereof being opposite-hand;

FIG. 6 is a sectional plan view taken along lines 6—6 in
FIGS. 1, 4 and 7;

FIG. 7 is a sectional view taken along lines 7—7 in
FIGS. 2 and 6, and

FIG. 8 is a transverse sectional view taken along lines
8—8 in FIGS. 1 and 7.
